UNITED STATES PATENT OFFICE.

CARL TONSAGER, OF MOORHEAD, MINNESOTA.

ELEVATING MACHINE.

Application filed November 6, 1919. Serial No. 335,997.

To all whom it may concern:

Be it known that I, CARL TONSAGER, a citizen of the United States, residing at Moorhead, in the county of Clay and State of Minnesota, have invented certain new and useful Improvements in an Elevating Machine, of which the following is a specification.

The invention relates to an elevating machine, and more particularly to the class of grain, sand, gravel or the like handling, or loading machines.

The primary object of the invention is the provision of a machine of this character, wherein grain, sand, gravel and other like substances can be elevated and delivered at the point of deposit, without necessitating the hand pitching and shoveling of the substance in the usual well known manner, the machine being mobile so that it can be transported from one locality to another and motor propelled.

Another object of the invention is the provision of a machine of this character, wherein the elevating conveyer is mounted relative to the power wheel which also acts as a substance lifter, in a novel manner, so as to avoid any possibility of the piling of the substance or the overflowing thereof during the exchange between the power wheel and said conveyer, thereby enabling the substance to be handled with dispatch and automatically during the working of the machine, thus eliminating hand labor.

A further object of the invention is the provision of a machine of this character, wherein the power wheel thereof is utilized as a part of the elevating mechanism, when the machine is at a standstill, the machine in its entirety being of novel construction and enabling the handling of substances expeditiously and without the use of hand labor.

The invention furthermore has for an additional object to improve machines of the indicated character, in varying particulars, to the end that efficiency and operation may be promoted, as well as simplicity in construction and convenience of adjustment and control.

The invention will be particularly explained in the specific description following:

Reference is to be had to the accompanying drawings forming a part of this specification, in which similar characters of reference indicate corresponding parts in all views.

Figure 1 is a perspective view of a machine constructed in accordance with the invention.

Figure 2 is a vertical longitudinal sectional view thereof.

Figure 3 is a vertical transverse sectional view taken through the elevating conveyer.

In constructing a practical embodiment of the invention in accordance with the illustrated example, the frame 10 is provided, preferably comprising spaced parallel side beams or sills 11 which have forwardly convergent end portions 12 meeting each other and integrally joined together, while the rear ends of said side beams or sills 11 are united with a rear cross axle 13 having a depending hanger 14 at one end supporting a wheel spindle 15 on which is journaled a relatively small ground wheel 16, while the other end of said axle 13 terminates in a wheel spindle 17 on which is journaled a relatively large power and traction wheel 18, the details of which will be hereinafter fully described.

Rotatably mounted in the forward end of the frame 10 is a vertical steering post, column or stem 19, which has its lower end fixed in a wheel fork 20 having journaled therein a front guide wheel 21, the upper end portion of the post, stem or column 19 being bent at right angles to form a steering lever 22 which is adapted to be manually controlled for the guiding of the machine in its travel.

Supported on the frame 10 forwardly thereof is a motor 23, preferably of the internal combustion type, although any other form of motor can be substituted if found desirable, the driving shaft thereof carrying a belt wheel or pulley 24 over which is trained a power transmission belt 25, the same being also trained over a belt wheel or pulley 26 fixed on one end of a driven shaft 27, the same being journaled in bearings 28 upon the frame 10, the said driven shaft being disposed transversely of the latter and having on its opposite end a belt wheel or

pulley 29 over which is trained a belt 30 the same being also trained over a drum 31 carried by the power wheel 18 at the outer side thereof. In this manner the power of 5 the engine or motor 23 will be transmitted directly to the said power wheel 18 for the advancement of the machine, the motor or engine 23 being controlled and regulated in any ordinary well known manner.

10 The power wheel 18, which may be termed what is known as a bucket wheel comprises a relatively broad flat tire or rim 32 provided at suitable intervals with traction cleats 33 and this tire or rim has secured 15 thereto on the outer side a guard ring or annular flange 34 which cooperates with an inner ring or flange 35 to provide an annular space at the inner periphery of said tire or rim, the space being broken up into a plurality of buckets by means of cross plates 36, which extend between the outer and inner rings or flanges.

Mounted upon the rear axle 13 and rising therefrom are spaced supporting yokes 37 25 and 38 respectively, the yoke 38 being of considerably greater height than the yoke 37 and on these yokes is mounted a transversely disposed laterally inclined conveyor frame 39 in which is arranged an endless 30 traveling conveyor apron 40, having the usual load sustaining cleats 41. The frame 39 is tilted in the direction of the wheel 18 and extends therein to a point above the axis of rotation thereof, the apron 40 being 35 driven from a roller 42 having on one end of its axle a belt wheel or pulley 43 over which is trained an endless belt 44 the same being also trained over a belt wheel or pulley 45 fixed to a countershaft 46 journaled 40 longitudinally of the frame 10 in bearings 47. The counter-shaft 46 has fixed thereto a bevel gear 49 meshing with a companion bevel gear 48 on the driven shaft 27, so that motion from the motor or engine 23 will be 45 transmitted to the apron 40 for the travel thereof in the conveyor frame 39 to elevate and deliver loads received from the bucket wheel in the operation of the machine and in a manner hereinafter fully described.

50 The lower end of the conveyor frame 39 is formed with a hopper 50 having the upwardly divergent opposed side walls 51, which have their upper edges terminating close to the buckets in the wheel 18 to positively receive the contents of these buckets which contents are discharged into the hopper 50, thereby assuring the exchange of the full capacity of the bucket into said hopper without any possibility of the over- 55 flowing or the loss of the substance in the elevation thereof during the working of the machine.

It will be observed that the outside flange or ring 34 is disposed at an angle so as to 60 deflect the substance within the bucket in

the wheel towards the hopper for the discharge of the contents of the buckets thereinto, the side walls of the hopper being designed to prevent the piling of the substance during the elevating period in the operation of the machine.

70 Detachably mounted upon the spindle 17 carrying the wheel 18 is a leg or prop 52 which is a frame work composed of bars of steel or other metal of such a length as to allow jacking the said ground wheel 18 in raised position so as to clear the ground when the machine is at a standstill, so that the said wheel 18 will serve to elevate material to the conveyor apron 40 when such 80 material is delivered into the buckets in said wheel. On the removal of the leg or prop 52 the wheel 18 will serve as a ground or traction wheel and constitute the power wheel of the machine for its transportation 85 from one point or locality to another.

90 In the operation of the machine when it is desired to advance the same the power wheel 18 is brought in contact with the ground and on the starting of the motor 95 the machine will travel to the desired location, the power from the motor 23 being transmitted directly to the wheel 18 for the advancement of the machine and the traction cleats 33 preventing the wheel 18 from 95 slipping upon the ground.

When it is desired to utilize the machine 100 for grain, sand, gravel or other material, the leg or prop 52 is mounted upon the spindle 17 and positioned so as to raise the wheel 18, thereby rendering the machine immovable and converting the power wheel 18 into a bucket wheel, the material being introduced into the buckets interiorly of said wheel and on the rotation thereof the said 105 material or contents of the buckets will be discharged onto the conveyor apron 40 which elevates the material and delivers the same at the desired point of deposit and at an elevation, the machine being useful for 110 loading granaries, truck or other load receivers or carriers. When the machine is used in this manner, the traction cleats 33 prevent material from banking about the wheel and so minimize resistance to its 115 rotary movement.

120 From the foregoing it is thought that the construction and manner of operation of the machine will be clearly understood and therefore a more extended explanation has been omitted.

What is claimed is:

125 A loading device comprising a portable frame, a rear axle, supporting wheels on said axle, one of said supporting wheels having a rim portion, rim flanges and flange connecting plates constituting internal pockets within the body of said wheel, the outer open side of the flange supporting wheel being unobstructed to permit mate- 130

rial to be thrown therein, a jack detachably connected to one end of said axle for supporting said flange wheel and frame in elevated position, whereby said wheel can be utilized for loading material when the frame is stationary, a transversely extending inclined conveyor, and supporting yokes

therefor attached to said axle, said conveyor having a hopper at its lower end extending within the body of the flange supporting wheel. 10

In testimony whereof, I hereunto affix my signature.

CARL TONSAGER.
